UNITED STATES PATENT OFFICE.

ELMER R. CORWIN, OF CHICAGO, ILLINOIS, ASSIGNOR TO CORWIN TELEPHONE MANUFACTURING COMPANY, A CORPORATION OF ILLINOIS.

TELEPHONY.

1,071,212.

Specification of Letters Patent. Patented Aug. 26, 1913.

Original application filed April 24, 1911, Serial No. 622,936. Divided and this application filed June 10, 1912. Serial No. 702,730.

To all whom it may concern:

Be it known that I, ELMER R. CORWIN, citizen of the United States, residing at Chicago, in the county of Cook and State 5 of Illinois, have invented a certain new and useful Improvement in Telephony, (this application being a division of the application, Serial No. 622,936, filed April 24, 1911,) of which the following is a full, clear, 10 concise, and exact description, reference being had to the accompanying drawings, forming a part of this specification.

My invention relates to telephone systems and in one of its aspects embodies an inter 15 or intercommunicating system, though it is to be understood that I do not limit this portion of my invention to systems located entirely within buildings since it is possible to effect intercommunication between the 20 telephones of my intercommunicating system whether such telephones are in the same building or in different buildings.

Some features embodied in my intercommunicating system are adapted for use elsewhere and are broadly claimed.

My present application is a division of my application Serial No. 622,936, filed April 24, 1911, the present case relating particularly to the intercommunicating system 30 which was disclosed in that application in connection with exchange equipment provided with mechanism for automatically effecting the extension of telephone lines.

I will explain my invention fully by reference to the accompanying drawings showing the preferred embodiment thereof, and in which—

Figure 1 is a diagrammatic view illustrating my improved intercommunicating system and certain apparatus for holding the automatically selectable trunk line which is shown in Fig. 2, and which also diagrammatically indicates certain well known automatic telephone exchange equipment, 40 though I do not wish to limit myself to automatic exchanges.

Referring now to the intercommunicating system of my invention I have shown three stations each having lines extending to 50 each of the other stations. The lines in the embodiment of the invention illustrated are metallic lines to which I do not wish to be limited. Station No. 1 thus has a metallic line 1-1 extending therefrom to each of the

other stations, similarly station No. 2 has a 55 telephone line 2-2 extending to each of the other stations, and station No. 3 has a telephone line 3-3 extending to each of the other stations. At each station there are a number of line selecting keys *a*, one individual 60 to each line extending to such station from another station, whereby each station may select any of the other stations, providing that the station to be selected is free for selection.

Assuming that the party at some intercommunicating station, say at station No. 1, desires communication with some other intercommunicating station party, say party at station No. 2, the first or calling intercommunicating station party will first remove his telephone receiver *b* from its switch-hook *c* thereby bridging his telephone apparatus across his line 1-1, such bridge being traceable from the upper pole 70 of the battery *e* through the impedance *f* of the calling line, the right hand armature switch of the now deenergized electromagnet or relay *g* and the normal contact of such armature switch, the transmitter *h* by way 80 of a dial switch mechanism *i* (which is here employed to select a trunk line but which should be replaced by a permanent connection between said armature switch and transmitter if the provision for automatic 85 selection of trunk lines were absent), the receiver *b*, the switch-hook *c* and the contact directly engaged thereby, the left hand armature switch of relay *g* and its normal contact, a second impedance *f*' of the calling 90 line to the lower terminal of the battery *e*. This bridge is desirably of low resistance as compared with the resistance of the right hand winding of relay *g* by which characteristic another line seeking line No. 1 cannot 95 then cause the energization of the relay *g* belonging to such line seeking line No. 1, which energization of such relay belonging to the seeking line is necessary as will hereinafter appear in order to enable a seeking 100 line to be telephonically connected with a line sought, such energization taking effect when said right hand winding of relay *g* belonging to a seeking line is bridged across the idle line being sought, there then being 105 no low shunt across the selected or called line, the transmitter and receiver at the station of such idle line being in open or very

high resistance bridge. It will also later appear how the presence of the bridge established at a calling station through the receiver and transmitter thereat will enable the manifestation of a busy test signal in the telephone receiver at another station that might be seeking the first calling line. The calling party having placed his telephone in bridge of the line for the purposes stated, 5 and later more fully to be explained, next fully depresses the selecting key a individual to the line of the party being called whereby the latch member k is fully depressed owing to the engagement of the pin a^1 with the inclined portion of the key a , such movement of the latch member k incidentally freeing the other pins a^1 from engagement with the associated key plungers to enable the springs associated with any previously 10 depressed key to restore the same to its initial position in which the pin a^1 is engaged with the key notch that is located nearest the key springs. This restoring movement of a previously actuated key occurs each 15 time any selecting key is depressed sufficiently to carry the pin a^1 below the points of the notches next adjacent and to the right of the pins. The latch member k carries two pins k^1 k^2 located above contact springs k^3 20 k^4 , the pin k^1 being closer to the spring k^3 than is the pin k^2 with reference to the spring k^4 . As the latch member k is moved downward one circuit is first established between the spring k^3 and its lower or alternate contact, and thereafter another circuit 25 is established between the spring k^4 and its lower or alternate contact. The first circuit includes the right hand high resistance coil of relay g , which coil may have a resistance, 30 say of 500 ohms, and which circuit may be traced from the upper pole of the battery e through the impedance f of line 2, the two uppermost contacts of the actuated key a , that key at station No. 2 which is individual 35 to line No. 2, the said right hand high resistance winding of relay g , contact spring k^2 and its alternate contact, the two lower contacts of said actuated key, the impedance f^1 of line No. 2, to the lower pole of the battery e . If the telephone at the called station 40 No. 2 is upon its hook then the bridge containing the same, which is say 50 to 100 ohms when closed, is not established across the called line so that the high resistance right hand coil of the relay g at the calling station 45 is not shunted by any low resistance path at the called station whereby the current from the battery is permitted to flow in sufficient volume through said right hand high resistance coil of the relay g , whereby the core 50 of said coil is effectively energized and the three armature switches associated with said core are operated to establish circuits that will be traced as follows: One circuit may be 55 traced from the upper pole of the battery e

through the impedance f of the calling line, the two uppermost contacts c^1 of the switch-hook c , the left hand coil of the relay g at the calling station No. 1 (which left hand coil may have a resistance of say 50 to 100 ohms) the intermediate armature switch of said relay, the spring k^4 and its normal contact (the actuated selecting key now being released to permit the pin a^1 to be bottomed in the notch nearest the key-head), the impedance f^1 of the calling line to the lower pole of the battery e . When the selecting key a has been released sufficiently to occupy its intermediate position, the circuit including the right hand coil of the relay g at station No. 1 is opened by reason of the separation of the spring k^3 from its alternate contact, but owing to the relationship of the springs k^3 k^4 with the pins k^1 k^2 the circuit through the left hand coil of said relay is closed before the circuit through the right hand coil is opened during the restoring movement of the actuated selecting key whereby the core common to the coils of the relay holds the armature switches in their positions. The relay g at the calling station is now included in a circuit that contains the uppermost contact c^1 of the switch-hook c at the calling station whereby the now only effective circuit for said relay is broken when the receiver at the calling station is restored to its switch-hook. The low resistance winding of the relay at the calling station is included in bridge of the calling line to take the place of the bridge previously established at the calling station through the transmitter and receiver thereat, but which latter bridge has been opened by the attraction of the right hand armature switch, this latter bridge depending upon said armature switch and its normal contact for its continuity when the associate receiver is off its hook. When the right hand armature switch of the calling station relay is attracted no high resistance winding of the relay at any station seeking connection with line No. 1 may become energized owing to the shunting action of said low resistance relay winding at the first calling station whereby the second calling station cannot secure telephonic connection with line No. 1. Another circuit established as a consequence of the energization of the relay at the calling station may be traced from the upper terminal of the battery e through the impedance f of the called line No. 2, the upper contact of the actuated selecting key at station No. 1 which is individual to line No. 2, the right hand armature switch of the relay at the calling station and its alternate contact, the connection between said armature switch and the transmitter h (whether such connection is permanently continuous or is normally made through a circuit-breaker i), the receiver b at the calling station, the switch- 100

hook *c* at the calling station, the left hand armature switch of the calling station relay, the contact spring *k*³ and its normal contact, the lowermost contacts of said actuated semi-restored selecting key, the impedance *f*¹ belonging to the called line, to the lower pole of the battery *e*. In this way the calling station telephone apparatus is supplied with talking battery and is transferred to a bridge connection between the sides of the called line, this transfer occurring immediately upon the release of the actuated selecting key to permit said key to occupy its intermediate position at which time the low resistance winding of said relay is placed in bridge of the calling line for the purposes previously stated. If the called party at station No. 2 has his telephone in use, a characteristic testing current would have flowed through the telephone receiver at calling station No. 1 during the time that the selecting key was fully depressed and which testing current would have found a circuit similar to that circuit which will hereinafter be described in connection with the telephone receiver at station No. 3 where circuit connections are shown that arise when a party seeking connection with a line across which a telephone bridge is established or the substitute for such bridge that includes the left hand low resistance winding of the relay *g* at the busy station being sought. The calling party at station No. 1 receiving no busy test signal, depresses his ringing key 1 and thereby includes the signal or bell *m* at the called station in circuit with a ringing battery *n*, which circuit may be traced from the upper pole of said ringing battery through the contacts of the ringing key 1, the lowermost contacts of the semi-released selecting key at station No. 1, the left hand armature switch of the relay *g* at called station No. 2 and the normal contact of such switch, the switch-hook *c* at the called station and its normal contact, the signal receiver *m* at the called station, thence to the lower pole of said ringing battery. The party at station No. 2 removes his telephone receiver *b* from its switch-hook, in response to the signal conveyed by the device *m*, and connects his transmitter and receiver in bridge of the line No. 2, whereby the transmitter at station No. 2 is supplied with battery current and telephonic connection is established with the calling party's telephone previously bridged across line No. 2, it being understood that the calling party's telephone bridge across line No. 2 guards line No. 2 against selection by and permitting a test signal to be furnished to a second calling line seeking connection with line No. 2. It is understood that the called party's relay *g* remains inert throughout the entire connection as the system is here organized.

It has been explained how the telephone

receiver at station No. 1 is in bridge of the line belonging to this station when the party there initiates a call and prior to the actuation of a selecting key at said station, whereby the calling line is guarded against selection by another calling party. It has also been explained how the calling party's telephone is placed in bridge of the called line and how a low resistance bridge including the left hand winding of the relay *g* at the calling station is substituted for the telephone receiver bridge that has been transferred from line No. 1 to line No. 2 whereby line No. 1 is still guarded against selection by another calling party. It will be understood that owing to the transfer of the calling party's receiver to a bridge connection between the sides 2 2 of the called line, such called line is guarded by such receiver bridge. When the parties are through conversation they restore their telephone receivers to their switch-hooks, battery *e* being excluded from circuit with the transmitter *h* at the called station No. 2 and also being excluded from circuit with the transmitter *h* at the calling station. The only circuit that previously remained closed for the relay *g* at calling station No. 1 is opened at the switch-hook *c* at the calling station when the telephone receiver thereat is restored thereupon. The equipments at both calling and called stations are now restored to normal so that either station may call or be selected.

I will now describe the testing circuit which prevails when the calling line seeks another line across which a low resistance bridge conductor has been placed either by the placing of a telephone receiver circuit across the line or a circuit of equivalent resistance, namely, the left hand low resistance winding of a relay *g* at another calling station. The equipment at station No. 3 is shown in the condition which it has when the party at such station seeks connection with the line across which one of the described low resistance bridges has been placed. By way of example, the party at station No. 3 is shown in the act of endeavoring to select station No. 1 which was previously described as being a station calling station No. 2. The party at station No. 3 removes his telephone from its switch-hook and thereafter fully depresses the selecting key *a* individual to line No. 1, belonging to station No. 1 and causes the establishment of a circuit that may be traced from the upper pole of the battery *e*, the impedance *f* of line No. 1, the uppermost contacts of the actuated key at station No. 3, the right hand winding of relay *g* at station No. 3, spring *k*³ at station No. 3 and the alternate contact of such spring, the lowermost contacts of the actuated key at station No. 3, the impedance *f*¹ of line No. 1, to the

lower pole of the battery *e*. Owing to the presence of the low resistance bridge across line No. 1 the relay *g* at station No. 3 will not be sufficiently energized to cause the 5 operation of its armature switches. The party at station No. 3 also receives a busy test manifestation owing to the establishment of a circuit which may be traced from the upper pole of the battery *e*, the impedance *f* of line No. 3, the right hand armature switch of relay *g* at station No. 3 and the normal contact of such armature switch, the connection that intervenes between said armature switch and the transmitter *h* at 10 station No. 3, the telephone receiver *b* at station No. 3, the switch-hook at said station, the left hand armature switch of relay *g* and the normal contact of such switch, the busy test contact spring *k*⁴ and its alternate contact, thence to the lower pole of 15 the battery *e* by way of the device *o* for causing such modification of the current flowing from the battery *e* as to produce a characteristic testing current to inform seeking parties of the busy condition of the 20 lines. The apparatus at the different intercommunicating stations is thus similar in equipment, function, arrangement and circuit association and similar parts are given 25 similar characters of reference.

In Fig. 1 station No. 1 is not shown as being a calling station with reference to station No. 2 though station No. 3 is shown as being a calling station with reference to station No. 1. Station No. 1, however, is 30 shown as being in calling or selecting relation with a trunk line leading to the automatic exchange shown in Fig. 2, and I will now describe the operations, the apparatus, 35 and circuit changes which occur when the party at an intercommunicating station seeks connection by means of a trunk line with a party whose line extends to an automatic exchange, each of the intercommunicating stations being preferably 40 equipped with apparatus whereby that connection with such trunk lines may be effected, though I do not wish to be limited to the 45 number of stations that may thus become connected with such trunk lines nor to the 50 association of such trunk lines with intercommunicating stations in all embodiments of the invention.

As I have shown in my invention, a plurality of trunk lines extend to each of the 55 intercommunicating stations, selecting keys *p* being provided at each intercommunicating station one individual to each trunk line at each intercommunicating station. I 60 have shown portions of two trunk lines *q* and *r* in Fig. 1 and in Fig. 2 have shown a continuation of one of these trunk lines, line *r*, to an automatic exchange. It is assumed that the party at intercommunicating station No. 1 has been in the act of ap-

propriating trunk line *r* to which end such party first removed his receiver from its switch-hook at his station. By this operation the party at station No. 1 included his receiver in low resistance bridge of his line 70 so as to guard his line and enable a busy test signal to be furnished to a party seeking his line in a manner which has been described. The calling party endeavoring to select the trunk line *r* next fully depresses 75 his key *p* that is individual to the trunk line in order to test the trunk line. It will now be assumed that such trunk line is idle (a busy test circuit being later traced over a busy trunk line). The seeking party at 80 station No. 1 next releases the actuated button *p* to permit the spring mechanism thereof to place said key in an intermediate position as shown whereby the calling party's receiver and transmitter are placed in bridge 85 between the sides of the selected trunk line owing to the energization of the relay *g*, the left hand winding of this relay *g* being placed in bridge of the line 1 1, all as will readily be understood from the previous description without further explanation, the four lower contacts of each key *p* having the same relation with the sides of the trunk line associated therewith as is possessed by the four contacts of each selecting key *a* 90 with respect to the line associated therewith and also possessing similar circuit relation with respect to the associate relay *g*. It may be said that the only distinction between the electrical environment of each 95 key *p* and each key *a* resides in the provision of the upper contact for each key *p* and certain connections to be mentioned leading from said contact and to the next contact beneath. With the key *p* in its intermediate position, the trunk line *r* is guarded by the telephone of station No. 1 bridged across the trunk line and line No. 1 is guarded by the left hand low resistance winding of the 100 relay at station No. 1 bridged between its 105 sides. Under the assumption that the trunk line is free, the calling party at station No. 1 will operate his dial mechanism in a well known manner, such dial mechanism being very familiar to those skilled in the art. By 110 means of this dial mechanism the wanted party shown at A is selected and connected with the trunk line and during the process of such connection a bridge including the magnet *s* and battery *t* is normally across 115 the sides of the trunk line in a manner familiar to those skilled in the art, the elements *s* and *t* being present in existing automatic telephone exchange equipment. If the party at station No. 1 should desire 120 for any reason to disconnect his telephone from the trunk line and at the same time prevent the operation of the releasing magnet *u* and male magnet *u*¹, which form other well recognized parts of automatic tele- 125

phone exchange equipment, and thereby prevent the disconnection of the called station A from the trunk line and be in position to resume connection with such trunk line and called station, such party at the calling station will fully depress the semi-released selecting key p and thereafter restore his telephone receiver upon its switch-hook and finally permit the said key p to become restored to its intermediate position. As a consequence of these operations relay g at the calling station is deenergized owing to the separation of the contacts e^1 . The relay v associated with the trunk line is bridged across the sides of the trunk line as a result of the full depression of the key p , such bridge connection being traceable from the lower side of the trunk line through the winding of the relay v , the two uppermost contacts of the key p to the upper side of the trunk. The armature of said relay v is attracted so as to maintain said bridge continuous when the key p is finally released, the bridge connection maintained by said armature switch being traceable from the lower side of the trunk line through the winding of the relay v , said switch and its contact to the upper side of the trunk line. The bridge including the elements s t having been previously established at the automatic exchange in accordance with well known practice, the circuit for the relay v is maintained closed, and, which is more to the point, the bridge which includes the relay v is maintained in order that the circuit through the magnet s and battery t may be unbroken during the time that the calling party's telephone is out of bridge relation with the trunk line so that during this time the releasing magnet u will not be operated at the called automatic station but will remain in connection with the trunk line. When the calling party desires to resume the connection of his telephone with the trunk line, he first removes his receiver from its switch-hook, fully depresses the previously actuated key p and then releases said key to permit it to occupy an intermediate position. As a consequence of these operations the calling party's telephone is again placed in bridge of the trunk line, the left hand winding of the calling party's relay is again placed in bridge of the calling line whereby the telephonic relation of the calling party's telephone with the trunk line is maintained. The relay v , being of high resistance, say 500 ohms, is now shunted by the calling party's telephone so that the entire calling and trunk line equipment is restored to that condition which was obtained when the calling party first secured telephonic connection with the called automatic station. As I have illustrated the equipment, any station of the intercommunicating system may select a trunk line

free for selection, each key p having similar control of the relay v , of which but one is shown to a trunk line, though I do not wish to be limited to the number of these relays. The relays v are located at one station where an attendant operator may be employed for the purpose of answering calls coming into the intercommunicating system by way of the trunk lines and manifested at the signal devices w in a manner and by mechanism and circuits which need not be described, the attendant being able to effect connection between trunk lines and the wanted intercommunicating lines. If the trunk line selected for use by the calling party had been busy then such calling party would have received a busy test manifestation by reason of the circuit established through his telephone receiver which he had removed from its switch-hook while holding the actuated button p in its fully depressed position which is the position of any actuated button a or p when a test is being made of the line individual thereto. The test circuit then established is well understood from the previous description and may be traced from the upper terminal of the battery e through the impedance f , the telephone b , the switch-hook c , the left hand armature switch of the calling party's relay g and the normal contact of such switch, the spring k^1 and its alternate contact, back to the battery by way of the device o for causing the fluctuation of the current flowing from the battery for testing purposes. Such flow of testing current is permitted because the right hand armature switch of the calling party's relay g is against its normal contact due to the fact that such relay g is not energized owing to the presence of the low resistance bridge established across the trunk line by some other intercommunicating station telephone. It will be unnecessary to describe the automatic telephone exchange equipment as such is well known by those skilled in the art. It is sufficient to state that the apparatus shown in association with the trunk lines at the intercommunicating stations cooperates in the manner which has been described with the magnet s and the battery t that determine whether or not the releasing magnet u of the automatically operated switching mechanism shall release the called automatic line. Inasmuch as I have provided equipment at the intercommunicating stations for automatically selecting called automatic subscribers I preferably employ the standard substation equipment in the intercommunicating system such as is furnished by the Automatic Electric Company of Chicago, Illinois for automatic exchange work, circuit environment being supplied thereto as is illustrated and as has been described. It is understood that such inter-

communicating station equipments each includes the selecting dial *i* for selecting the called line and the receiver *b* and telephone switch-hook *c* operating to open the circuit 5 including the elements *s* and *t* when the receiver is restored upon its switch-hook for the purpose of setting the automatically operated switching mechanism at the automatic exchange into operation to release 10 the called line, all as is well understood by those familiar with the art. I do not wish to be limited however, to any special style of station mechanism or automatic exchange mechanism, nor do I wish to be limited to 15 other precise details of construction and circuit arrangement which I have herein shown and particularly described as changes may readily be made without departing from the spirit of my invention. An 20 important feature of my invention however, resides in the fact that I am enabled to hold the trunk line *r* by a circuit established over its metallic sides and without the necessity of employing additional circuits. In cer- 25 tain of the claims I claim the trunk lines broadly as telephone lines, as my invention is not to be limited to trunk lines.

Having thus described my invention I claim as new and desire to secure by Letters 30 Patent the following:—

1. An intercommunicating telephone system including three or more telephone lines, a busy test circuit, apparatus at the stations serving partially to establish the busy test 35 circuit and common to said lines, and means for completing the busy test in coöperation with apparatus at the station of the line

seeking connection with the line taken for use.

2. An intercommunicating telephone sys- 40 tem including three or more telephone lines, the stations of said telephone lines having electro-magnetic mechanism for connecting station telephones with the telephone lines of the remaining stations of said lines, and 45 means brought into operation by lines taken for use for altering the operative condition of the electro-magnetic mechanism at the station of a line seeking connection with a line taken for use to prevent connection of 50 the telephone at this line seeking station with the line taken for use.

3. An intercommunicating telephone sys- 55 tem including three or more telephone lines, the stations of said telephone lines having electro-magnetic mechanism for connecting station telephones with the telephone lines of the remaining stations of said lines, shunts for the electro-magnetic mechanism, and means brought into operation by lines 60 taken for use for altering the condition of the shunt for the electro-magnetic mechanism at the station of a line seeking connection with a line taken for use to prevent connection of the telephone at this line seek- 65 ing station with the line taken for use.

In witness whereof, I hereunto subscribe my name this second day of November A. D., 1911.

ELMER R. CORWIN.
